United States Patent Office

Des. 192,609
Patented Apr. 17, 1962

192,609

IRON HOLDER

Frederick Marx, Sr., 2205 N. 7th Ave., Lake Worth, Fla.

Filed Feb. 23, 1961, Ser. No. 64,021

Term of patent 14 years

(Cl. D49—6)

Fig. 2

Fig. 3

Fig. 4

FIG. 1 shows a perspective view of an iron holder showing my new design.

FIG. 2 is a front elevational view thereof.

FIG. 3 is a bottom plan view thereof.

FIG. 4 is a side elevational view thereof.

I claim:

The ornamental design for an iron holder, substantially as shown.
